Patented Jan. 16, 1973

225,967

HANGER FOR PICTURES, MIRRORS, PLAQUES OR THE LIKE

Lee Richard Chasen, Port Chester, N.Y., assignor to Coats & Clark, Inc., New York, N.Y.

Filed June 11, 1971, Ser. No. 152,478

Term of patent 14 years

Int. Cl. D8—08

U.S. Cl. D8—257

FIG. 1.

FIG. 2.

FIG. 2.

FIG. 3.

FIG. 4.

FIG. 1 is a front view of the hanger, for pictures, mirrors, plaques or the like, the side opposite being similar in appearance.

FIG. 2 is a side view;

FIG. 3 is a top view; and

FIG. 4 is a bottom view.

I claim:

The ornamental design for a hanger for pictures, mirrors, plaques or the like, as shown and described.
